UNITED STATES PATENT OFFICE.

FELIX EMILE VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

AWL MOTION.

1,418,751.

Specification of Letters Patent. Patented June 6, 1922.

Application filed August 1, 1918. Serial No. 247,748.

To all whom it may concern:

Be it known that I, FELIX EMILE VALOIS, a citizen of the United States, residing at Haverhill, county of Essex, State of Massachusetts, have invented a certain new and useful Improvement in Awl Motions, of which the following is a specification, reference being had therein to the accompanying drawings.

10 My invention relates to an awl feed for sewing machines of the type in which the work is fed by the action of an awl. The particular object of the invention is to provide actuating mechanism for the awl feed 15 which shall be simple and effective and capable of being run at a high rate of speed. The mechanism may be made very strong and is without links so that there is no lost motion and the mechanism will operate 20 perfectly in hard thick material as well as in soft stock. The forward and backward feeding movements of the awl are given it by a cam while the penetrating and retracting movements are produced by a variable 25 speed rotating crank. This is a wholly novel arrangement and contributes greatly to the speed and smoothness of the machine. In the following description no reference is 30 made to the other parts of the sewing machine of which the awl feed forming my present invention is a part, as an understanding of the details of the remainder of the machine is not necessary for the understanding of the present invention.

35 The invention will be fully understood from the following description when taken in connection with the accompanying drawings and the novel features thereof will be pointed out and clearly defined in the claims 40 at the close of this specification.

In the drawings, Fig 1 is a top plan view partly in section of a portion of a sewing machine embodying my invention.

Fig. 2 is a vertical elevation partly in section of the parts shown in Fig. 1.

Fig. 3 shows the parts in another position.

Fig. 4 is a detail of the mechanism by which the awl sector is actuated, the parts being in the position as shown in Fig. 3.

50 Fig. 5 is a detail showing a modified form of construction.

Referring now to the drawings, at A is shown the needle and B the work table and at C the looper. The main shaft of the ma-

chine is designated D and actuates the 55 shaft E by which the awl feed is driven. The shaft E is for convenience called a differential shaft and moves at a varying angular velocity as compared with the angular velocity of the main shaft D which is constant. The shafts A and E are parallel but out of axial alinement and carry, respectively, the cranks F and 11 provided 60 respectively with stud-pins connected by a pitman in the form of a disk G apertured 65 to receive them, as represented more particularly in Fig. 1. Variable rotary motion is imparted to the shaft E from the main-shaft D in a manner well known, as disclosed for instance, in the United States patent to McCloskey, No. 184,644, of November 21, 1876.

At 12 is shown the awl and at 13 the awl sector oscillatable on the awl shaft 15 carried by a slide 16. The said slide 16 is 75 mounted in ways 17 secured to a fixed part of the machine. The movement of the slide 16 is parallel with the axis of the differential shaft E. On the said differential shaft E is located a cam 18 in the groove of which 80 travels a cam roll 19 mounted on the rear end of a lever 20. The lever 20 is pivoted at 21 to a fixed portion of the machine and is slotted as shown at 22 to receive a block 23 pivoted at 24 to a lever link 25. The 85 lever link 25 is provided with a handle 26 by means of which the block 23 may be moved in the slot 22. The other end of the lever link 25 is pivotally connected at 27 to the slide 16. By moving the lever link by 90 means of the handle 26, the effective length of the lever 20 may be regulated and the rapidity of feed varied accordingly. The mechanism just described causes the awl to make one complete movement toward the 95 needle to feed the work forward and a backward movement after the awl has been withdrawn from the work, the whole movement being accomplished by one revolution of the differential shaft E and having variations 100 in velocity corresponding to the variations in angular velocity of the differential shaft.

The awl sector is oscillated about the awl shaft 15 by means of a connecting rod 29 the lower end of which is formed into a socket 105 30 which surrounds a ball 31 secured to the awl sector. The other end of the connecting rod is secured to the ball race 3 of a

self-aligning ball bearing, the balls of which are shown at 32. The cup 33 or other member of the ball bearing is secured to the pin of the crank 11. Ball bearings of the self-aligning type are well known to those skilled in the art and are constructed to permit a movement of the ball race out of its normal plane without causing the balls to be cramped between the ball race and the ball cup. This construction, therefore, permits the needle sector to be moved on the slide 16 a sufficient distance to feed the work and this movement of the needle sector on the slide 16 does not interfere with the free operation of the connecting rod 29 on the crank 11.

In Fig. 5, I have shown a connecting rod 40 and crank pin 41 the contacting surfaces of which are spherical to permit movement 20 of the connecting rod out of its normal plane exactly as is permitted by the self-aligning ball bearing. I prefer however to employ the form shown in Figs. 1 to 4 since this machine may be run more safely at high 25 speed. Both forms of my machine are the same in principle, since both have spherical bearing surfaces of the crank pin and connecting rod, permitting movement of the connecting rod out of its normal plane.

30 In the operation of the herein described machine, the awl penetrates the work and then remains stationary so far as the further upward movement is concerned while the feeding of the work by the cam 18 takes 35 place. Since it is necessary to have the awl stationary in the work during the forward feeding movement of the feed slide, this feeding movement is timed to take place just before the crank 11 reaches its extreme position 40 toward the awl sector so that the further movement of the crank 11 is just sufficient to compensate for the increased distance from the centre of the ball and socket joint 31 to the axis of the crank pin 11. 45 This will be better understood if this line is considered as the hypotenuse of a right angled triangle, one side of which is the distance from the centre of a ball 31 to the axis of the crank pin and the short side of which 50 is the amount of the forward feeding movement of the awl sector. Since the hypotenuse is longer than either side of the triangle, it results that a slight retraction of the awl out of the work would result if the forward 55 feeding movement of the awl took place after the crank 11 had reached its extreme forward position. To obviate this difficulty the forward movement of the awl is caused to take place just before the extreme position 60 of the crank 11 is reached so that an advance of the connecting rod 29 takes place which is just sufficient to prevent retraction of the awl.

What I claim is:

65 1. An improved awl feed for sewing ma-

chines of the character described, comprising means for giving to the awl its forward and backward feeding movements, and a variable speed-rotating crank to give to the awl its penetrating and retracting movements. 70

2. An improved awl feed for sewing machines of the character described comprising means for giving to the awl its forward and backward feeding movements, a main shaft having a uniform angular velocity, a rotating crank to give the awl its penetrating and retracting movements, and variable speed mechanism connecting the main shaft and the crank so that the crank shall be 75 driven at varying angular velocities relatively to the main shaft. 80

3. An awl motion for a boot and shoe sewing machine comprising, a slide, an awl sector oscillatably mounted on said slide, a rotating shaft, a crank on said shaft to oscillate the sector, a cam on said shaft, and connections by which the slide is actuated by the cam. 85

4. In a four motion awl feed, a slide, an awl sector oscillatably mounted thereon, a rotating shaft, a crank on said shaft, a connecting rod between said crank and said sector, and means for actuating said slide 90 in time with the sector. 95

5. In an awl feed mechanism for sewing machines, a slide, an awl sector oscillatably mounted thereon, a rotating shaft, a crank on said shaft, mechanism to reciprocate said slide, yielding connections between the crank 100 and the sector through which the crank actuates the sector while permitting movement of the slide.

6. In combination, an oscillatable awl sector, means to give the awl sector a bodily feeding movement in a line transverse to the plane of oscillation, a rotating crank and a jointed yielding connection between the crank and the sector. 105

7. In combination, a rotating shaft, a crank and a cam thereon, a slide, an oscillatable awl sector mounted thereon, connections through which the slide is actuated by the cam, and yielding connections between the crank and the sector through which the crank actuates the sector while permitting movement of the slide. 110 115

8. In combination, a shaft, a crank on said shaft, a slide, an oscillatable awl sector mounted thereon, means to actuate the slide, a connecting rod for the crank, having a universal joint connection with the sector, and there being a connection intermediate the sector and the crank permitting movement of the sector in a plane transverse to the plane of rotation of the crank. 120 125

9. In an awl feed mechanism for sewing machine, a slide, an awl sector oscillatably mounted thereon, a rotating shaft, a crank on said shaft, and yielding connections to 130

transmit motion from the crank to the sector while permitting movement of the slide and sector.

10. In combination, a shaft, a crank on said shaft, a slide, an oscillatable awl sector mounted thereon, means to actuate the slide, a connecting rod, having a universal joint connection with the sector, and a self-aligning ball bearing interposed between the 10 crank and the connecting rod.

11. In combination, a shaft, a crank on said shaft, a slide, an oscillatable awl sector mounted thereon, means to actuate the slide, a connecting rod having a universal 15 joint connection with the sector and there being spherical proximate bearing surfaces for the crank and connecting rod, and a self-aligning ball bearing interposed between the crank and the connecting rod.

20. 12. In a device for operating upon material, a penetrating element, a rocking carrier therefor mounted to perform feeding movements in the direction of the axis of its rocking movements, means for imparting to said 25 element work penetrating and withdrawing motion including a rotary actuating member and a single element pitman connection between the same and said carrier, and mechanism for imparting to said element work 30 feeding motion, said means acting during said feeding motion to compensate for changing relative position of said element thereto whereby said element may remain substantially stationary relative to the work 35 during such feeding motion.

13. In an awl feed mechanism, an awl, a rocking carrier therefor, a rotary crank for

imparting to said awl work penetrating and withdrawing motion a direct pitman connection between said crank and carrier, and 40 mechanism for imparting to said awl work feeding motion, said crank moving during said feeding motion to compensate for changing position of said awl thereto whereby said awl may remain substantially stationary 45 relative to the work during such feeding motion.

14. In an awl feed mechanism, an oscillatable curved awl, a carrier therefor, means including a rotary actuating member and a 50 single element pitman connection between it and said carrier for oscillating said awl to penetrate and withdraw from the work, and mechanism for imparting to said awl work 55 feeding motion, said means acting during said feeding motion to compensate for changing relative position of said awl thereto whereby said awl may remain substantially unoscillated during said feeding motion.

60 15. In an awl feed mechanism, an oscillatable curved awl and a carrier therefor, a variable speed crank and a pitman connection between the same and said carrier for oscillating said awl to penetrate and withdraw from the work, and mechanism for imparting to said awl work feeding motion, said crank moving during said feeding motion to compensate for changing position of said awl whereby said awl may remain substantially unoscillated during said feeding motion.

65 In testimony whereof I affix my signature.
FELIX EMILE VALOIS.
